UNITED STATES PATENT OFFICE.

RANKIN TEMPLE DAVENPORT, OF WILLIAMS, ARIZONA.

TELEGRAPH-REPEATER.

1,111,566.

Specification of Letters Patent. Patented Sept. 22, 1914.

Application filed November 7, 1913. Serial No. 799,679.

To all whom it may concern:

Be it known that I, RANKIN T. DAVENPORT, a citizen of the United States, and a resident of Williams, in the county of Coconino and State of Arizona, have invented a new and Improved Telegraph-Repeater, of which the following is a full, clear, and exact description.

This invention relates to a single line telegraph repeater, and it has for its general objects to increase the speed of transmission of telegraph signals repeated from one line to another; to improve and simplify the construction of the apparatus so as to be reliable and efficient in use, and to eliminate objectionable features in existing repeaters.

Single line repeaters heretofore proposed make use of transmitters or double contact relays in combination with holding coils or shunt devices which materially lessen the speed of signaling. It is well known in the operation of repeaters of this kind that there must be a short-time interval between the opening of the line relay and the opening 25 of the opposite line at the transmitter contact so as to allow the shunt or holding coil to operate before the opposite line is opened. This materially shortens the signals and reduces the speed of transmission, and the 30 inertia of the transmitter lever also contributes to this result. These objections are overcome by a novel arrangement of circuits, relays and contact devices whereby incoming signals can be directly repeated 35 into the opposite line by the receiving relay without the use of a transmitter. The relays may be of any suitable type, provided the movable contact or armature of each is normally biased to a closed circuit position 40 in order that the lines are normally closed through the repeater. Polarized relays are especially useful in this connection, although a light retractile spring may be used to hold the armature in closed circuit 45 position; or the base of the relay may be inclined, as in the case of the "Horton" repeater. Polarized relays may be connected differentially, as in duplex or quadruplex telegraphy, but it is preferable to 50 connect each pair of coils in a separate circuit, as will be hereinlater more fully described.

In the accompanying drawing which illustrates certain embodiments of the invention, and wherein similar characters of reference indicate corresponding parts in both the

views, Figure 1 is a diagrammatic view of a repeater of the polarized relay type; and Fig. 2 shows a modified form of relay for use in the repeater.

Referring to the drawing, A and A', B and B', designate the two pairs of polarized relays which are embodied in the repeater, the relays A and A' serving to repeat on line 2 an incoming message received from line 1, and the relays B and B' serving to repeat on line 1 a message received from line 2. The relays A, A' and B, B' consist respectively of circuit-closing magnets M', M², M³, M⁴, circuit-opening magnets R', R², R³, R⁴, movable contacts or armatures 5, 6, 7 and 8, fixed contacts or front stops 10, 11, 12 and 13, and back stops 10^a, 11^a, 12^a and 13^a. In order to hold the armatures in closed position when the closing and opening magnets are deenergized, each armature has connected thereto or associated therewith a permanent magnet 9. The cores a of the electro-magnets are adjustable into proper relation to their respective armatures, any suitable means of adjustment being provided, such as the pinion b that meshes with rack teeth c on the core extension d, so that by turning the pinion the core can be moved 85 toward or from its armature.

The lines 1 and 2 are connected by wires e and e' respectively with the contacts 7 and 5 of the relays B and A. The contacts 10 and 12 are respectively connected by wires f and f' with one terminal of the electro-magnets M³ and M'. The other terminals of such magnets are connected by wires g and g' with the electro-magnets M², M⁴, such lateral magnets being in turn connected by wires h and h' with main batteries 20 and 20^a, that are connected to ground. In other words, the magnets M' and M² are connected in series with each other and with line 1 and battery 20, and the magnets M³ and M⁴ are connected in series with each other and with line 2 and battery 20^a. The other magnets of the relays are connected in local circuits. The magnets R' and R² are connected in series by the wire i, one terminal of the magnet R' being connected to ground at j through a local circuit battery k, while the magnet R² is connected by a wire l to ground at m through the contacts 8 and 13. The magnets R³ and R⁴ are connected in series with each other by a wire i', the magnet R³ being connected to ground at

j' through a battery *k'*, and the magnet *R*⁴ being connected by a wire *l'* to ground at *m'* through contacts 6 and 11. The wires *l* and *l'* contain switches *S* and *S'* which can 5 be thrown to a position to connect the said wires respectively with the grounded wires *n* and *n'*. The movable contacts 6 and 8 of the relays *A*' and *B*' are connected respectively with sounders *o* and *o'* which are in 10 turn connected to ground through a battery *p* and *p'*. A shunt *S*² containing a switch *s*² is arranged around the contacts 7 and 12 of the relay *B*, and a shunt *S*³ containing a switch *s*³ is arranged around the contacts 5 15 and 10 of the relay *A*.

Concerning the magnets of each polarized relay, it is to be observed that when no current is flowing in either of the opposed coils or electro-magnets, the armature between 20 them will remain against either its front or back stop, provided the cores are equally distant from it. When the core of the right-hand magnet is closer to the armature the latter will remain against its front stop. If 25 there is current flowing in both magnets in such a direction as to give to the ends adjacent to the armature similar polarity, but opposite to the polarity of the armature, the latter will be attracted toward the core 30 which exerts the strongest magnetic pull upon it, this pull varying directly as the ampere turns on the coil and approximately inversely to the square of the distance between the inner ends of the core and the 35 armature.

In describing the operation of the repeater, it will be assumed that the cores of the right electro-magnets are nearer their respective armatures than are the cores of the left electro-magnets, and that the current flowing 40 through, or the magnetic flux produced by, the former is stronger than the current flow in, or magnetic flux of the latter, so that when current is flowing through the various 45 magnets the armatures will be in closed circuit position or in engagement with the front stops. Now, if an incoming signal is transmitted over the line 1 by the opening 50 of a distant sending key therein, the magnet *M*' is deenergized, and consequently the armature 5 is attracted to open circuit position by the magnet *R*', which is in a closed 55 circuit consisting of the battery *k*, magnet *R*', wire *i*, magnet *R*², wire *l*, contacts 8 and 13, ground *m*—*j*. The moving of the contact 5 to open circuit position opens the receiving line or main 2, so that the signal received over the line 1 will be directly transmitted to the receiving line 2. Simultaneously with the opening of line 2 by the armature 5 the local circuit containing the magnets *R*³ and *R*⁴ will be opened by the armature 6 moving out of engagement with the contact 11 through the deenergizing of 60 the magnet *M*² and attraction of the magnet 65

*R*². The magnets *M*³ and *M*⁴ are also deenergized when line 2 is opened by the movement of the armature 5 of relay *A* to the left, but since magnets *R*³ and *R*⁴ are deenergized simultaneously with *M*³, and *M*⁴, 70 armatures 7 and 8 are held in their closed position by their permanent magnets, so that neither line 1 nor the local circuit of magnets *R*' and *R*² are opened by the opening 75 of relays *A* and *A*'. When line 1 is again closed by the sending key at the distant station the magnets *M*' and *M*² of the relays *A* and *A*' will be reenergized so as to restore 80 the armatures or contacts 5 and 6 to normal position, thereby again closing the receiving line or main 2 and the local circuit containing 85 magnets *R*³ and *R*⁴. This opening and closing of line 2 is repeated in true synchronism with the opening and closing of the sending line 1 in the transmission of dot, dash and space signals. Obviously the repetition of signals from line 2 to line 1 is effected in the same manner, except that the magnets *M*³ and *M*⁴ will be the ones that 90 respond to the opening and closing of the line 2, and the armatures 7 and 8 will move to open and closed position accordingly. 95

By means of sounders *o* and *o'*, batteries *p* and *p'* and keys *K*' and *K*², the repeater attendant is enabled to communicate with 100 stations on either line. When switches *S* and *S'* are thrown to the ground wires *n* and *n'*, and switches *s*² and *s*³ are thrown to closed circuit position, the repeater is cut and each line may be operated independently. 105

The modification shown in Fig. 2 is a single relay intended to take the place of the double relays *A* and *A*' or *B* and *B*'. The magnets *M*⁵ and *R*⁵ correspond respectively to the magnets *M*' and *M*², and *R*' and *R*², and the contacts 5^a and 10^a correspond to the contacts 5 and 10 of relay *A*, and the contacts 6^a and 11^a correspond to the contacts 6 and 11 of relay *A*'. It will be noted that there is a small space between 110 the tips of contacts 5^a and 6^a which provides for 6^a and 11^a opening before 5^a and 10^a. Obviously many other arrangements of armature and fixed contacts for the main line and local circuits may be provided to 115 accomplish the results described.

From the foregoing description taken in connection with the accompanying drawing, the advantages of the construction and method of operation will be readily understood by those skilled in the art to which the invention appertains, and while I have described the principle of operation, together with the apparatus which I now consider to be the best embodiment thereof, I 120 desire to have it understood that the apparatus shown is merely illustrative and that such changes may be made when desired 125 as are within the scope of the appended claims. 130

Having thus described my invention, I claim as new and desire to secure by Letters Patent:

1. The combination of line wires, with a repeater connected between the wires and comprising a relay for each line, each relay having its coil in one line wire and its contacts in the other line wire, and electromagnet means for opening the contacts when the coil is deenergized. 10
2. The combination of line wires, with a repeater connected between the wires and comprising a relay for each line, each relay including an electro-magnet in one line wire and contacts in the other line wire, said contacts being held in closed circuit position by said magnets when energized, and magnets tending to open circuit the contacts whereby the opening and closing of one line wire causing the opening and closing of the other line wire. 15
3. The combination of line wires over which signals are received and repeated, with a repeating apparatus comprising two sets of co-acting circuit closing and opening electro-magnets, normally closed line wire contacts associated with and operated by each set of said magnets, the circuit closing magnets of one set being in circuit with the line wire contacts of the other set, a local circuit for each of the circuit opening magnets, and normally closed local circuit contacts associated with and operated by each set of magnets, whereby the circuit opening magnets coacting with the circuit closing magnets connected with the receiving line will be deenergized with the opening of the receiving line, and the circuit opening magnets associated with the circuit closing magnets connected with the sending line will remain energized to open the contacts of the receiving line. 25
4. The combination of line wires over which signals are received and repeated, with a repeating apparatus comprising polarized relays A, A' and B, B', each relay comprising opposed circuit-closing and opening electro-magnets and normally closed circuit-opening and closing armatures movable to closed circuit position by said closing magnets and to open circuit position by said opening magnets, said relays A and A' having their circuit closing magnets connected with one line through the armature of relay B, and the relays B and B' having their circuit closing magnets connected with the other line through the armature of relay A, local circuits including respectively the opening magnets of relays A and A' and the armature of relay B', and relays B and B' and the armature of relay A', keys between the lines and armatures of relays A and B, 30 and sounders in circuit with the armatures of relays A' and B'. 35
5. The combination of line wires over which signals are received and repeated, with a repeating apparatus comprising polarized relays A, A' and B, B', each relay comprising opposed circuit-closing and opening electro-magnets and normally closed circuit-opening and closing armatures movable to closed circuit position by said closing magnets and to open circuit position by said opening magnets, said relays A and A' having their circuit closing magnets connected with one line through the armature of relay B, and the relays B and B' having their circuit closing magnets connected with the other line through the armature of relay A, local circuits each having one side grounded and including respectively the opening magnets of relays A and A' and the armature of relay B' and opening magnets of relays B and B' and the armature of relay A', keys between the lines and armatures of relays A and B, grounded circuits including sounders in series with the armatures of relays A and B. 40
6. The combination of line wires over which signals are received and repeated, with a repeating apparatus comprising polarized relays A, A', and B, B', each relay comprising opposed circuit closing and opening electro-magnets and normally closed circuit opening and closing armatures movable to closed circuit position by said closing magnets and to open circuit position by said opening magnets, said relays A and A' having their circuit closing magnets connected with one line through the armature of relay B, and the relays B and B' having their circuit closing magnets connected with the other line through the armature of relay A, local circuits including respectively the opening magnets of relays A and A' and the armature of relay B', and relays B and B' and the armature of relay A', keys between the lines and armatures of relays A and B, 45 and sounders in circuit with the armatures of relays A' and B'. 50
7. The combination of line wires over which signals are received and repeated, with a repeating apparatus comprising polarized relays A, A', and B, B', each relay comprising opposed circuit closing and opening electro-magnets and normally closed circuit opening and closing armatures movable to closed circuit position by said closing magnets and to open circuit position by said opening magnets, said relays A and A' having their circuit closing magnets connected with one line through the armature of relay B, and the relays B and B' having their circuit closing magnets connected with the other line through the armature of relay A, local circuits each having one side grounded and including respectively the opening magnets of relays A and A' and the armature of relay B' and opening magnets of relays B and B' and the armature of relay A', keys between the lines and armatures of relays A and B, grounded circuits including sounders in series with the armatures of relays A and B. 55

relays A' and B', switch containing shunts in parallel relation with the armatures of relays A and B, and a switch for grounding each local circuit at a point between the opening magnets and the armature therein.

5 In testimony whereof I have signed my

name to this specification in the presence of two subscribing witnesses.
